[57] CLAIM

The ornamental design for a pool chair, as shown and described.

DESCRIPTION

FIG. 1 is a perspective view of a pool chair showing my new design;

FIG. 2 is a front elevational view;

FIG. 3 is a right side elevational view, the left side being a mirror image thereof;

FIG. 4 is a top plan view;

FIG. 5 is a bottom plan view; and,

FIG. 6 is a rear elevational view thereof.

The broken line showing of the side edge of a pool, in FIG. 3, is for illustrative purposes only and forms no part of the claimed design.
